UNITED STATES PATENT OFFICE.

VINCENT RAGONA, OF BROOKLYN, NEW YORK, ASSIGNOR TO CARY MANUFACTURING CO., OF BROOKLYN, NEW YORK, A CORPORATION OF NEW YORK.

PACKAGE-BINDING IMPLEMENT.

Application filed September 19, 1922. Serial No. 589,150.

This invention is an implement for applying a wire binder to shipping packages of various forms.

In this art it is required that a wire be applied initially under tension to the package, and while under such tension, it is required, further, that the end portions of the wire be locked or fastened. It is desirable to tension the wire binder so tightly around the package as to embed said wire in the corners of the package, whereby the wire binder increases the stability of the package, and the wire itself is precluded from movement upon or relatively to the package to avoid the requirement of using staples, or other fasteners, for holding the wire in place. Furthermore, it is desirable to lock or fasten the end portions of the binder by twisting said meeting end portions together.

The object of this invention is to perform the operations of tensioning and of locking the wire binder by or through the instrumentality of a single operating member, thereby facilitating the desired application of the binder to the package and simplifying the structure of the implement.

Stated broadly, the implement of this invention embodies a single operating member positioned for convenient access to the workmen, a suitable tension means, a suitable twisting means, and a train of gears controllable in a manner for one of said gears to actuate the tension means and for another of said gears to rotate the twisting means, said gear train being actuated by or from the single operating member.

Other functions and advantages of the invention will appear from the following description taken in connection with the accompanying drawings, wherein—

Figure 1 is a plain view of the implement in operative position upon a package and illustrating the wire binder prior to the application of tension thereto.

Figure 2 is a vertical sectional elevation taken in the plane indicated by the dotted line 2—2 of Figure 1.

Figures 3 and 4 are vertical cross sections, partly in elevation, the plane of the respective sections being indicated by the dotted lines 3—3 and 4—4 of Figure 1.

Figure 5 is a detail sectional view, part-

ly in elevation, illustrating the movable part of one form of a suitable wire tensioning means.

Figure 6 is a plan view of a wire binder subsequent to its application to a package.

Figure 7 is a detail view of one of the retainers used for holding a preformed deformed wire.

The implement of my invention is shown as being adapted for use in connection with a shouldered wire binder, X shown in Figures 1 and 6, said wire being preformed and deformed in one way or another to produce the shoulder x adjacent the end portion of the wire, and said wire being cut to a length suitable to be passed around the package Y, in a manner for the end portions of said binder to overlap sufficiently for the performance of the operation of twisting together, as at y, said end portions to thereby lock or fasten the wire into tight engagement with the package. The wire in the present instance is deformed by a swaging operation which is performed upon the wire at the time it is drawn from a reel or coil, straightened, and cut to lengths, such treatment of the wire taking place before it is to be used for binding purposes; in fact, the wire is prepared, bundled in quantities, and shipped to the consumer so as to be available for use by said consumer without further treatment or manipulation other than that manipulation accorded to the wire by the implement in applying said wire to the package.

The deformation of the wire heretofore alluded to is for the double purpose of producing the shoulder x thereon and of changing the cross sectional contour of said wire so as to result in a flattened portion x' adapted to serve as a key in order to facilitate the introduction of an end portion of the wire into a recessed member A of the machine, whereby the shouldered and key formed portions of said wire are retained or anchored in fixed relation to the implement and the introduction of said wire into the implement is facilitated.

The implement is constructed with a suitable frame for accommodation of the working parts, a part of said frame being a housing B shown as comprising complementary members b, b assembled into lateral contact-

ing engagement and suitably fastened together. The housing is shown as having a flat under face or bottom *e* and as being provided with a forwardly extending member 5 *C*, the upper face *c'* of which slopes toward a horizontal slot *C'*, the latter being provided in the members *b*, *b* of the housing. The retaining plate *A* is fixedly attached to one side of the housing and is provided with 10 an appropriate recess *a'* indicated in Figure 7 of the drawings, said recess being in alignment with the slot *C'* of said housing, whereby the deformed key portion *x'* of the wire is adapted to be introduced into the plate *A* 15 for the purpose of anchoring the wire at one end on the housing or frame of the implement, as a result of which the strain on the wire when tension is applied thereto is taken up by the shoulder *x* in abutting contact 20 with said plate *A*, so that the shoulder holds the wire from slipping with respect to the machine in the operation of tensioning said wire.

D is a plate fixed to the opposite side of 25 the housing from plate *A*, see Figs. 1 and 4. This plate *D* is provided with a recess *d*, and said plate is in fixed relation to the housing for the recess *d* therein to be in alignment with slot *C'* of the housing and 30 with the recess heretofore mentioned as being provided in retaining plate *A*. The two recessed plates *A*, *B*, fixed to the housing, and the slot *C'* in said housing itself, accommodate the lapping end portions of the 35 binder wire, when said wire is passed around the package, see dotted lines in Fig. 1, and said plates *A*, *B*, hold or retain the lapping portions of the wire from relative movement at two points during the operation of twisting 40 said wire at *y* by the rotative movement of a twister gear *E*, see Fig. 3. The slot *d* in plate *D*, and a corresponding slot in plate *A*, are sufficiently wide to receive the wire, but the width of said slots is less than twice 45 the diameter of the wire, so that the two end portions of the wire when positioned in the slots of the plates *A*, *D* are held by said plates from turning one around the other when the wire is twisted by the rotation of 50 twister gear *E*, although it is to be noted that the slots in plates *A*, *D* permit the wire to slide endwise with freedom in the operation of pulling said wire to impart the desired tension to the wire prior to the twisting 55 together of said wire by the rotation of the twister gear.

As shown, the housing members *b*, *b* are recessed at *e* to accommodate the twister gear which is mounted for free rotation in 60 said housing, and this twister gear *E* is provided as usual with a radial slot *e'* for the reception of the lapping portions of the wire.

Cooperating with the twister gear *E* is 65 an intermediate gear *F*, the shaft *f* of which

is journaled in housing *B*, and this gear *F* is adapted to be rotated at the required time for the operation of the twister gear by a gear *G*, constituting one of a train of gears adapted to be controlled and actuated by 70 a single operating member, the latter being cooperable with tensioning means and with the twisting means in a manner to impart movement from a single operating part to both said tensioning means and the described twisting means. 75

Said operating member is shown as a shaft *H* provided with a hand crank *h*, although it is not desired to limit the invention to this particular kind of power applying contrivance, for the reason that equivalent hand operated mechanical devices can be substituted for the crank operated shaft, as will be readily apparent to a skilled constructor. As shown in Figs. 1 and 2, the single operating shaft *H* is horizontally arranged with respect to the machine, the same being journaled in appropriate bearings *h'* provided in the members *b*, *b* of the housing. In the particular embodiment of the invention depicted in the drawings, the single operating shaft *H* is rotatable and 80 slideable in the housing, and said housing is chambered at *i* for the accommodation of the power transmitter gear *G* so as to encase 85 said gear and to permit it to have the desired sliding movement within said housing, said gear *G* being fixedly secured to shaft *H* for rotative and sliding movement therewith. In one position of the shaft *H* and gear *G*, shown in Fig. 2, said gear is free 90 from the intermediate gear *F*, hence the rotation of shaft *H* and its gear *G* will have no effect upon gear *F* and the twister *E*, but a sliding movement of shaft *H* to the left in 95 Fig. 2 brings gear *G* into mesh with gear *F*, so that a rotative movement of shaft *H* will operate to turn the gear *G* which in turn imparts rotative motion to the twister 100 through the action of intermediate gear *F*. 105

Various forms of wire tensioning means may be employed for pulling said wire to impart the required tension thereto, but in the drawings there is shown one kind of tension device for pulling the wire around the package when one end of said wire is anchored in the retaining plate *A* of the implement frame, said tensioning means being actuated by gears *J*, *K*, constituting other members of the gear train, the latter being operable and controllable by the single operating member, i. e., shaft *H*. The gear *J* is fixedly attached to shaft *H*, at one end thereof, and exteriorly to the housing *B*, and in one position of the shaft *H*, the gear *J* is adapted to mesh with gear *K*, the latter being also positioned exteriorly to said housing, see Figs. 1 and 2. Said gear *K* is secured fixedly to the end of a screw spindle *L*, the latter being provided with a plain sec- 115 120 125 130

tion l and journaled in a bearing as at l' (see Fig. 2) for free rotation in the housing, said screw spindle being horizontally positioned and arranged below the operating shaft H , and disposed so as to extend a desired distance from one side of housing B .

Cooperating with the screw spindle is a tension head, herein shown as a slidable traveler M , the latter being positioned along-
5 side the housing B and adapted for movement toward and from said housing, laterally with respect thereto. Said traveler is shown as having an upstanding perforated lug m and an aperture m' , said lug being
10 fitted loosely on the operating shaft H , and said aperture m' loosely receiving a guide rod m^2 , whereby the shaft H and rod m^2 serve as means for directing or guiding the traveler to movement in a rectilinear path
15 with respect to the housing. The rod m^2 is fixed to the housing in a suitable manner, so that it is parallel to the screw spindle and to the operating shaft. Said traveler is provided, also, with a recess n and it is pierced
20 for the loose reception of the screw spindle, the latter passing through the traveler intermediate the ends of the latter. The traveler carries a half nut N , pivoted by loosely fitting the same on the guide rod
25 m^2 , see Fig. 5, and at the free end of the half nut is a latch n' controllable by a knob n^2 and adapted for locking engagement with said traveler so as to retain the threaded portion n^3 of said half nut into threaded en-
30 gagement with the screw part of the spindle, whereby the rotative motion of the spindle communicates sliding movement to the traveler.

For quickly returning the traveler to a normal position adjacent the housing after the wire shall have been tensioned, cut, and twisted, the operator disengages the latch n' and lifts the half nut from contact with the screw spindle, whereupon a spring N' acts
40 on the upwardly extending lug m of the traveler to press the latter toward the housing, said spring N' being loosely fitted on the shaft H for one end of the spring to engage with the extension m of said traveler. To provide for the fixed attachment of the wire to the traveler, suitable means are used on said traveler for engagement with the wire. As shown, the traveler is provided at one end with a shoulder o , in
45 which is provided a notch o' and to which is attached a post O . One end portion of the wire is conducted out of the twister, through plate D , and bent upwardly around shoulder o , and in the notch thereof, the wire being
50 twisted around post O , see Fig. 1, so as to anchor said wire in fixed engagement with the traveler.

For cutting the wire subsequently to the operations of tensioning and twisting the same, a cutter in the form of a lever P is

positioned alongside of slotted plate D and in cooperative relation thereto. Said lever is fulcrumed on a stud p fixed to housing B , and as shown by dotted lines in Fig. 4, the lower end portion of the cutter lever is notched at p' , to straddle one strand of the wire, whereas the cutting edge of the lever P is adapted in the operation of the lever to sever the other strand of the wire i. e., that strand which is anchored to the traveler. The cutter lever is thus limited in its action to severing one length of the wire and at a point close to the twist y in said wire, thus avoiding the formation of an outstanding cut end of the wire, see Fig. 6. The cutter lever extends upwardly from the pivotal stud p , and to this upper end is connected a spring q , acting to hold the lever out of the path of the two strands of wire. Said cutter lever is in the path of a cam arm Q fixed to the shaft f of the twister actuating gear F , and as said twister E is rotated to twist the wire at y , the cam arm impinges on the cutter lever so as to force it into contact with one strand of the wire with sufficient force to cut through the wire and to thus release the wire from the twister.

The operation may be described as follows:—The implement is placed upon the package with sufficient space between one side of said package and the crank h , after which the deformed and shouldered portions of a wire is introduced into the retaining plate A , so as to anchor one end of said wire on the machine frame. The wire is led into the slot e' of the twister and slot d of the plate D , and then the wire is passed around the package, the free end of said wire being passed through the slot of plate A , the slot of twister E , and the slot of plate D , and finally the wire is bent upwardly into notch o' and fastened around the post O' . The operator now grasps crank h and shifts the shaft H for the gear J to mesh with gear K , see Fig. 2, (gear G being out of mesh with gear F) and the shaft H is then rotated by turning crank h , the effect of which is to impart rotative motion to the screw spindle L through the gears J, K . The screw spindle imparts sliding motion to the traveler, the latter pulling on the wire, one end of which is attached to said traveler and the other end of which wire is anchored on the frame housing of retainer A . The crank h is turned a number of times until sufficient tension is applied to the wire, and then the operator slides the shaft H so as to disengage gear J from gear K (see Fig. 1) and positions gear G in mesh with gear F (see Fig. 3), the screw L operating at this time to hold the traveler against movement and thereby retain the wire under tension around the package. The operator now turns the crank h and shaft H for the gears G, F to impart rotative motion to the twister E , and

as the two end portions of the wire are held by the plates A, D from turning, the twister E operates to twist together the two ends of the wire at y between the plates A, D. As the twister makes the required number of turns, being driven by the large gear F, the cam Q, acts on the lever P to force the cutting edge against that length of the wire which is anchored in the traveler, thereby releasing the wire from said traveler and allowing the wire to remain in a highly tensioned and locked condition around the package. The implement is now removed from contact with the wire and the package, and the spring N' acts to return the twister to its normal position relatively to the housing B, and the shaft H is adjusted by sliding it in the housing to bring the gear J into mesh with the gear K, so as to place the implement in condition for operation upon another wire.

In my machine the single power member and the power transmitting gears operate to impart movement first to the tensioning means and thereafter to the twisting means, and in the interval between the operations of the tensioning means and the twisting means by the movement of the power member, said power transmitting gears are controllable, preferably by a sliding movement of the power member, so as to shift said gears out of operative relation to the tensioning means and into a similar relation to the twisting means. Thus there takes place a gear shift, operated manually between the operations of the tensioning means and the twisting means, or vice versa, and both said means (tensioning and twisting) are operated separately from and by the single power member acting through the power transmitting means.

Having thus fully described the invention, what I claim as new and desire to secure by Letters Patent is:

1. In a wire tying device, the combination with a twister pinion, and a tensioning member, of a shaft provided with a gear, means actuated by the shaft to impart sliding movement to said tensioning member, a rotatable and slidable operating shaft, a gear fast with the operating shaft and movable by the sliding movement thereof into and out of mesh with said gear on first named shaft, and a second gear fast with said operating shaft and movable by the sliding movement thereof into and out of service relation to said twister pinion, whereby the operating shaft is adapted in one position for actuating the twister pinion and in another of its positions to impart movement to the tensioning member.

2. In a wire tying device, the combination with a twister pinion, of wire tensioning means including a plurality of members one of which is fixed and the other of which is

slidable relatively to said fixed member, a shaft having means for imparting movement to said slidable member of the tensioning means, a gear on said shaft, a rotatable and slidable operating shaft, a gear on said operating shaft and movable by the sliding movement thereof into and out of mesh with the gear on the first named shaft, and another gear also fast with the operating shaft and movable by the sliding movement thereof into and out of service relation to the twister pinion.

3. In a wire tying device, the combination with a twister pinion, of wire tensioning means including a plurality of members one of which is fixed and the other of which is slidable relatively to said fixed member, a screw shaft co-operating with the slidable member of said tensioning means for imparting motion thereto, a slidable and rotatable operating shaft, and gears co-operating respectively with said screw shaft and said twister pinion, certain of said gears being movable with the operating shaft in the sliding movement thereof, whereby said operating shaft may impart rotative motion alternately to the screw shaft and to said twister pinion.

4. In a wire tying device, the combination with a twister pinion, of tension means including a plurality of members one of which is fixed and the other of which is slidable relatively to said fixed member, of a slidable and rotatable operating shaft, means actuated by said operating shaft when shifted to one position for imparting a sliding motion to the slidable tension member, and other means actuated by said operating shaft when shifted into a second position for imparting rotative motion to the twister pinion.

5. In a wire tying device, the combination with a twister pinion, of tension means including a sliding member and a fixed member having means for anchoring a deformed part of a wire to be tensioned, a sliding and rotating operating shaft adapted by the sliding motion thereof to be shifted to either of two operating positions, means actuated by said operating shaft when in one of its positions for imparting movement to the sliding tension member, and other means actuated by the operating shaft when occupying the other of its operating positions for imparting rotative movement to said twister pinion.

6. In a wire tying device, the combination with a twister pinion, of a tension means including a plurality of members one of which is slidable, a screw shaft, means actuated by the screw shaft for imparting movement to the slidable tension member, a sliding and rotating operating shaft, and a plurality of gears whereby the operating shaft imparts rotative motion alternately to the screw shaft and to the twister pinion.

7. In a wire tying device, the combination with a twister pinion, of a tension means including a plurality of members one of which is slidable, a screw shaft, a member pivoted to the slidable tension member and engageable with the screw shaft, a sliding and rotating operating shaft, and gears whereby

the operating shaft is adapted to impart rotative motion alternately to the screw shaft and to the twister pinion. 10

In testimony whereof, I have hereunto signed my name, at the State of New York, this eighteenth day of September, 1922.

VINCENT RAGONA.
